FLEXIBLE LADDER

Rosaria Forlano Morealdi D', East Boston, Mass.

Application March 29, 1948, Serial No. 17,696

2 Claims. (Cl. 228—40)

1

This invention relates to novel and useful improvements in ladder constructions for use in many environments.

An object of this invention is to support an individual while climbing to or descending from an elevation or to an elevated position in such a manner that upon fracture of one of the cords forming a portion of the loop ladder associated therewith, the rung will not descend, thereby causing an accident.

Another object of this invention is to safely remove individuals from burning buildings and the like.

Another object of this invention is to provide an improved ladder composed of a single rope, which rope is so arranged in loops and knots as to support rungs of the ladder whereby upon fracturing of one or two of the portions of the rope, the rungs will not fall.

Ancillary objects and features of novelty will become apparent to those skilled in the art, in following the description of the preferred forms of the invention illustrated in the accompanying drawings, wherein:

Figure 1 is a perspective view of a pouch or basket which may be used in carrying small children in descent from the higher elevations of a building, ship or the like, to a lower elevation;

Figure 2 is a plan view of a portion of needle-work wherfrom the concept of the present invention springs;

Figure 3 is a detailed view showing the method of forming the needle-work shown in Figure 2;

Figure 4 is a view somewhat similar to Figure 3, showing the second step of operation;

Figure 5 is a perspective view showing a fragmentary portion of a building with the instant invention applied thereto;

Figure 6 is a fragmentary elevational view of the first embodiment of the present invention;

Figure 7 is an enlarged fragmentary detailed view showing the method of making the loops and knots forming the instant invention and pertaining to the first embodiment thereof;

Figure 8 is a fragmentary elevational view of a second form of the invention;

Figure 9 is a detailed view illustrative of the method of making the second form of the invention;

Figure 10 is an elevational view of a portion of a third embodiment of the invention;

Figure 11 is a detailed view illustrating the method of making the ladder shown in the third form of the invention;

Figure 12 is an elevational view of the first

2

form of the invention showing the selected ropes broken;

Figure 13 is an elevational view of the second form of the invention, showing selected ropes broken; and

Figure 14 is an elevational view of the third embodiment of the invention, showing selected ropes broken therein.

This invention and more specifically, the inventive concept springs from and is a development of that concept taught in my patents, Numbers 2,407,031 and 2,402,568. These patents teach and show needle-work which cannot unravel when one of the cords thereof is broken and the method of making the needle-work. The principle of the present invention is to supply a ladder which will not fail to support the individual upon the fracture of one of the strands supporting the ladder. As in my patents, the concept of failing to unravel when a cord is broken, the present invention contemplates the failure to avoid maintaining the rungs and therefore the individual on the rungs of the ladder in the advent of fracture of one of the supporting portions of the single rope which either forms a portion of the rungs or actually supports wooden, metallic or other types of rungs.

Attention is now directed to Figure 7 wherein the first embodiment of the invention is illustrated. The portion of the safety ladder illustrated has rungs and means for supporting the rungs made from a single strand of rope. This single strand of rope has a knot generally indicated at 8 thereon and a loop 10 extending therefrom.

A portion 12 of the said rope extends from the knot 8 and forms a second knot 14 similar to the said knot 8 at the apex of the loop 10. Then, the rope continues to form a third knot 16 with a second loop 18 extending therefrom. A portion of the rope forming the second loop 18 extends to the apex of the first-mentioned loop 10 and forms a fourth knot 20 therein. Then, a continuation 22 of the said knot 20 projects through the third knot 16 and is adapted to extend to the apex of the second loop 18 and form a fifth knot, thereby initiating this procedure again. A rung 11 having an aperture 13 therein rests partially on the fourth knot 20 and on the said knot 14 with the knot 16 thereover.

The above description illustrates both the method of making the sides of the ladder of the first embodiment of the invention and the actual structure resulting from this method. Referring now to Figures 1 through 4, the evolution of the invention may be seen. In Figure 2,

there is illustrated needle-work 100 composed of a single strand of material. The method of fabricating this needle-work may be seen in Figures 3 and 4. A knot 102 is made by taking a piece of cord 104 and making a loop 106 therein. Then, the end of the loop is spiralled at 108 and the end of the spiral of rope extends through the loop 106. By pulling the end of the rope or cord 104, the knot 102 is formed. It will be noted that the spiral extends through a loop 110 which has been previously formed in the needle-work piece 100.

Referring now to Figure 4, this second step in the operation of making the needle-work is illustrated. This second step is for the actual formation of the loop 110. The needle 112 having the cord entrained through the eye thereof is utilized in both operations of making the knot 102 and loop 110, as is dictated by convenience.

The terminal 114 of the said knot 102 is formed in a loop 116, the cord of the said loop 116 continuing through the existing loop 110 and through the said loop 116, thence it is pulled tightly. By pulling the cord tightly as described herein, a loop 110 having a twist 120 is formed.

By the manipulations of a single thread, rope, or string or any other equivalent as described above, a piece of needle-work will result as is seen at 100 including a plurality of knots and loops with twists therein. By shearing or fracturing certain threads within the needle-work, it will not unravel as is the difficulty with the majority of conventional fabrics and more specifically the majority of handmade needle-work, with the exception of that needle-work disclosed in my patents identified previously herein.

Referring to Figure 1 now, it will be seen that a cradle generally indicated at 124 is supplied with loops 126 and 128 forming a portion thereof. These loops are of course, adapted to be held while a small child, infant or pet may be placed in the body portion of the cradle and lowered with an individual down a ladder. It is within the purview of the present invention to form the fabric of the cradle of the needle-work material or of the weave illustrated therein.

Going now to Figure 7 and in conjunction with this embodiment of the invention previously set forth, it may now be seen that a single rope of the ladder is looped and knotted in such a manner for supporting the rungs 11 whereby upon fracturing of one or two of the cords (see Figure 12) the rungs 11 will yet be maintained in spaced position for safe ascent and descent.

Referring now to Figure 9, a slightly modified form of the invention is disclosed. This slightly modified form includes a rung 11 having an aperture 15 adjacent each side thereof, which aperture is relatively larger than the above described aperture 13. In this form of the invention, there are no ropes or portions of the rope extending exteriorly of the rungs 11 and the said rungs bear on the knots 16 with the knots 20 and 14 being positioned thereover. This embodiment of the invention is utilized mainly to illustrate the versatility of the invention, whereby it may be strung from either end and the rungs 11 may seat upon any of the knots provided for seating purposes.

Attention is directed primarily to Figure 13, wherein it is disclosed that upon failure of any of the ropes or more specifically, the portions of the ropes forming the lateral supports for the rungs, the latter will remain effectively intact for safety purposes. Furthermore, in the event of

fracture of the portions of the rope which connect the knots 16 to the said knots 14 and 20, the latter will still maintain intact as the remaining portions of the rope will support the rungs.

Referring now primarily to Figure 11, the third illustrated form of the invention is made solely from a single piece of rope. Starting at the lower portion of the illustrated ladder for convenience, a knot 40 is illustrated having a loop 42 extending therefrom. The loops and knots in this embodiment as in the second embodiment, are formed as described in conjunction with the first form of the invention.

A portion 44 of the said rope extends from the knot 40 and forms a rung. Formed at the opposite end of the rung is a second knot 46 which is similar to the said knot 40. A second loop 48 projects from the said second knot 46 and a portion 50 of the rope forming the second knot 46 has a third knot 52 formed therein which receives the apex of the loop 48 therein. This portion of the rope also extends from the third knot to form a side loop 54, which side loop 54 has a knot 56 made medially of the length thereof. This medial knot is utilized for the purpose of preventing separation of the strands of the side loop 54.

At the terminal portion of the said side loop 54 is supplied a fourth knot 58 which is received adjacent the apex of the loop 48 and then, continues to form another rung 60. A fifth knot generally indicated at 62 is formed at the opposite end of the said rung 60 and receives the said first loop 42 therein adjacent the apex thereof. Then, the second side loop 64 extends from the said fifth knot 62. A lateral knot 66 for prevention of separation of the strands of the second side loop is formed medially thereof and the end portion of the said second side loop 64 has a sixth knot 68 formed therein which also takes in the said first loop 42 adjacent the apex thereof. The said single piece of rope then extends through the said lateral or side knot 66 for continuation to form a portion of another loop partially shown at 70. Of course, this procedure continues until the desired length of ladder is formed. By the above described structure in connection with the third embodiment of the invention, it will be readily appreciated by inspection of Figure 14 that various strands or portions of the single piece rope may be fractured or broken without unraveling.

Attention is now directed primarily to Figure 5 wherein one form of the invention is illustrated in use. There is shown a building structure having the usual window therein and the window encasement 80 appurtenant thereto. Eye bolts 82 may be supplied in the window casting in order to accommodate the chains 84 and 86 detachably therein, through the medium of a clamp 88. These chains 84 and 86 along with complementary chains (unnumbered) support a platform 90 substantially below the window sill 92. Truss members 94 are secured to the under-surface of the said platform 90 and are adapted to bear against the wall of the building structure. By so positioning the platform 90 before the sill of the window, fire, flames and the like may not impinge directly thereon which might escape through the open window.

Apertures are formed in the said platform 90 in order to accommodate knots 98 which are formed at the two ends of the said rope forming the ladder. It is readily appreciated that the

ladder may be suspended in this manner for ascent and descent to and from a building.

From the foregoing, an understanding of the article of the invention, method of making the same and utility thereof is deemed apparent. However, it is understood that variations may be made without departing from the spirit of the invention. Therefore, limitation is sought only in accordance with the scope of the following claims.

Having described the invention what is claimed as new is:

1. In a safety ladder stile including a vertical rung supporting portion, said vertical portion being formed from a single length of rope having first and second ends, the first end of said rope being tied to an intermediate portion of said rope to form a closed elongated loop, said loop being knotted intermediate its ends, the second end of said rope extending upwardly through said knot and being gripped by the knot, said rope having a pair of spaced knots engaged with said loop with the portion of the rope between the two knots forming an additional loop.

2. In a rope ladder including a pair of rung supporting portions, each of said portions being formed from a single length of rope having first and second ends, said first end being tied to an intermediate portion of said rope to form a closed elongated loop, said loop being formed

into a knot intermediate its ends, the second end of said rope extending upwardly through the knot formed in said loop and being gripped by the knot, said rope having a pair of spaced knots engaged with one end of the loop above the knot formed in the loop, the portion of said rope between said spaced knots forming another elongated loop, said last mentioned loop also being formed into a knot intermediate its ends, the second end of said rope being extended upwardly through the knot formed in the last named loop, said rope including a second pair of spaced knots engaged with the last named loop, and a rung extending between said vertical portions and having apertured ends seated on the first named knots of each vertical portion and located between the first named knots of the vertical portions and the knots in the last named loops of the vertical portions.
